By *J. D. Gruwaef, Atty.*

UNITED STATES PATENT OFFICE.

WALTER A. HEINRICH, OF ST. LOUIS, MISSOURI, ASSIGNOR TO W. N. MATTHEWS AND BROTHER, INC., OF ST. LOUIS, MISSOURI, A CORPORATION OF NEW MEXICO.

REFLECTOR.

1,315,494.

Specification of Letters Patent.

Patented Sept. 9, 1919.

Application filed June 24, 1918. Serial No. 241,610.

To all whom it may concern:

Be it known that I, WALTER A. HEINRICH, a citizen of the United States, residing at the city of St. Louis, State of Missouri, have 5 invented a certain new and useful Improvement in Reflectors, of which the following is a full, clear, and exact description, such as will enable others skilled in the art to which it appertains to make and use the same, reference being had to the accompanying drawings, forming part of this specification, in 10 which—

Figure 1 is a side elevational view of my improved guarded lamp reflector.

15 Fig. 2 is a front elevational view of the reflector.

Fig. 3 is a cross sectional view.

Fig. 4 is a detail view of the hook.

This invention relates to a new and useful improvement in reflectors for use in connection with electric lamps having what is commonly known as a lamp guard, the object being to construct the reflector in such a way that it can be quickly removable to 20 and from position. In the form shown in the drawing, the electric lamp is arranged in the socket on the end of a handle, and the lamp guard shown is a well known commercial form concerning which no claim is 25 made here. This lamp guard is preferably provided with a hook by which it may be suspended. The wires leading to the lamp extend through the bottom of the handle,—the whole construction being simply shaped 30 and convenient.

In the drawings, 1 indicates the wires leading to the lamp through the bottom of the handle 2 on which is a socket 3 for the usual electric lamp 4. 5 is the lamp 40 guard having a hook 6 by which the lamp may be suspended. This hook 6, as shown in Fig. 4, is preferably soldered to the upper ring wire and has its lower end flattened and formed into an eye which embraces the 45 middle ring wire. The hook is preferably soldered to the upper ring wire so as to secure it in position.

The numeral 7 is a semi-ovoidal reflector 50 preferably formed of metal so shaped as to engage at its lower contracted end the lamp socket 3 and at its upper enlarged end the top supporting wire of the lamp guard.

The numeral 8 indicates a securing bail, crimped as shown, and pivotally mounted in openings in the opposite edges of the reflector. The central portion of this bail is bent to form a hook 8^a which, when the reflector is placed in position, may be swung upwardly to engage the middle spacing wire of the lamp guard, thus securely holding 55 the reflector in position. The purpose of crimping the bail is to enable it to be easily adjusted as to its length when the reflector is used on lamp guards of different sizes. By elongating the bail, the hook will move 60 in a larger arc and can thus accommodate the reflector to a larger sized lamp guard. While I have described my invention as 65 a reflector for guarded lamps wherein said reflector is preferably made of polished metal, it is obvious that when opaque, the reflector can also be used as a deflector where high powered electric lamps are employed 70 for the purpose of obscuring the direct rays of light from the user.

75 It will be readily understood that minor changes in the size, form and construction of the various parts of my improved reflector may be made and substituted for those herein shown and described, without departing from the spirit of my invention, the scope of which is set forth in the appended 80 claims.

What I claim is:

1. A reflector for guarded lamps comprising a semi-ovoidal shaped reflector designed to be placed outside of the guarded lamp, and a bail pivoted to said reflector and embracing the guarded lamp opposite the reflector and having means for securing the reflector to the lamp guard. 85

2. A reflector for guarded lamps adapted to be fitted against the outside of the guarded lamp, in combination with a crimped bail provided with a hook for engaging the lamp 90 guard to hold the reflector in position.

3. A semi-ovoidal shaped reflector in combination with a crimped bail pivotally mounted thereon, said bail having a hook at its medial portion, and a lamp guard 95 with which said wire-hook co-operates.

4. A lamp guard composed of longitudinally disposed members and ring wires, and a suspending hook member bent to engage 100

the medial ring wire, said hook member being secured to the upper or outer ring wire.

5. The combination of a lamp guard in-
6 closing an electric lamp, and an opaque deflector removably attached to the outside

of said guard and arranged at one side only thereof.

In testimony whereof I hereunto affix my signature this 20th day of June, 1918.

WALTER A. HEINRICH.
